UNITED STATES PATENT OFFICE.

GODFREY HESS, OF WILLIAMSPORT, PENNSYLVANIA, ASSIGNOR OF THREE-FOURTHS TO HENRY METZGER, OF SAME PLACE, AND GEORGE W. DYER, OF WASHINGTON, DISTRICT OF COLUMBIA.

SOCKET AND CONNECTION FOR ELECTRIC-LIGHT CIRCUITS.

SPECIFICATION forming part of Letters Patent No. 325,540, dated September 1, 1885.

Application filed March 13, 1885. (No model.)

To all whom it may concern:

Be it known that I, GODFREY HESS, of Williamsport, in the county of Lycoming and State of Pennsylvania, have invented a certain 5 new and useful Improvement in Sockets and Connections for Electric-Light Circuits, of which the following is a specification.

The principal object I have in view is to produce a simple form of electric night-lamp 10 for use in multiple-arc systems of lighting by electric incandescence.

Heretofore the most efficient form of electric night-lamp has been obtained by the employment of two incandescent lamps connected together through a switch, by which they could be thrown into series in the same circuit. The lamps being designed to have the normal incandescence when in separate circuits, the result of throwing them into series in the same 15 circuit was to reduce largely the degree of incandescence and to produce an illuminating effect less than that produced by one lamp at normal incandescence. The dim light thus obtained was found suitable for a night-lamp.

The night-lamp as heretofore constructed required the use of a switch and connections of some complication for throwing the lamps from a multiple are to a series relation, and when the lamp-sockets employed were without circuit-controllers, (keyless sockets,) as 20 was frequently the case, it was not possible to use less than both lamps at full incandescence.

By my invention the switch and connections therewith referred to are dispensed with and a night-lamp is produced in which one lamp can be used at full incandescence for full light and the two lamps in series for the dim light. This I accomplish by the production of a short-circuiting lamp socket, which is connected in 25 series with a key-socket (one having a circuit-controller making and breaking the circuit) of ordinary construction. The short-circuiting lamp-socket has a circuit-controller which in one position short-circuits the lamp carried by 30 it and in the other position throws such lamp into circuit. Lamps being placed in these two sockets and the key of the ordinary socket being turned to close the circuit, the two

lamps can be thrown into series or one lamp 50 short-circuited and the other given its full or normal incandescence by the manipulation of the key of the short-circuiting socket. By means of the key of the ordinary socket the circuit can be opened and closed for throwing 55 the light off and on whether full or dim.

The short-circuiting lamp-socket is a device of simple construction. I take an ordinary key-socket and arrange the connections so that the circuit-controller will close a short-circuit 60 instead of breaking the circuit entirely.

In the lamp-socket at present used in the Edison system of lighting by electrical incandescence one of the circuit-terminals is a screw-ring and the other is a spring, which is thrown 65 up by the key against the tip of the lamp to close circuit and is drawn out of contact with such lamp-tip to break circuit, the spring resting upon insulation in this second position. By extending the flange of the screw-ring under 70 the end of this spring so that the spring will rest upon such flange when withdrawn from contact with the lamp-tip, a short circuit will be closed from the spring to the ring, cutting the lamp out of circuit in the second position of the spring.

The two lamps of my night-lamp may be arranged together or separated to any desired extent.

The resistance-lamp (the one in the short-circuiting socket) may be in sight, or it may be hidden from view in any suitable way, and this lamp need not be of the standard resistance of the system; but (especially if hidden from view) it can be of any desired resistance 85 to give in the other lamp the desired degree of incandescence.

The principle of my short-circuiting socket and its connection in series with an ordinary socket containing an electric lamp may be 90 employed for other purposes than the specific one described. It can be used for introducing any form of translating device into circuit in series with a lamp, such translating device being mounted upon the short-circuiting socket or connected therewith by wires running 95 to an attaching-plug placed like a lamp in said socket.

In the accompanying drawings, forming a part hereof, Figure 1 is an elevation of a night-lamp arrangement embodying my invention, the tubes being in section to show the wires. Fig. 2 is a view, principally in diagram, of the night-lamp arrangement; Fig. 3, a similar view showing the invention applied to introducing into circuit other translating devices than lamps. Fig. 4 is a vertical section of the preferred form of short-circuiting socket, and Fig. 5 a view, similar to Figs. 2 and 3, of a modification.

A is a short-circuiting socket having for one terminal a screw-ring, B, and for the other terminal a spring, C. The upper end of this spring is horizontal, and rests, when down, upon the flange *a* of the screw-ring B.

The circuit-controlling stem or key D raises the spring from *a* when turned in one direction, and when turned in the other direction permits the spring to rest upon such flange.

In the ordinary key-socket, which is shown at E in Figs. 2 and 3, the flange of ring B is on the opposite side of the socket and is not touched by such spring, which rests upon insulation when withdrawn from contact with the tip of the lamp.

F and G are the two lamps of the night-lamp, F being placed in the short-circuiting socket and G in the ordinary socket.

The sockets A and E are shown in Fig. 1 as mounted upon the arms of a V-shaped tube, *b*.

In Fig. 3 an attaching-plug, H, is shown in the short-circuiting socket, from which extend wires 1 2 to any translating device it is desired to introduce into circuit in series with lamp G.

The sockets A and E are connected in series, as shown. A wire, 3, extends to ring B of socket A, from spring C of which wire 4 runs to ring B of socket E, and from spring C of socket E extends a third wire, 5.

The wires 3 and 5 are connected with the

positive and negative conductors of the electric-lighting system, the devices described being in one of the multiple-arc circuits of such a system.

It is evident that a keyless socket (one without a circuit-controller) could be used in place of socket E, in which case the stem or key D of socket A could be arranged to give the spring C an intermediate position, touching neither flange *a* nor the lamp-tip and opening the circuit to both lamps. This modification is shown in Fig. 5.

What I claim is—

1. The combination of an electric-lamp socket having a short-circuiting circuit-controller and an ordinary lamp-socket connected in series, substantially as set forth.

2. The combination, with an electric-lamp socket having a short-circuiting circuit-controller, of a lamp-socket having a simple circuit opening and closing device, such sockets being connected in series, substantially as set forth.

3. An electric night-lamp wherein are combined a lighting-lamp, a resistance-lamp, and one or more circuit-controllers throwing the lighting-lamp into and out of circuit separately or in series with the resistance-lamp, the latter only being thrown into circuit in series with the lighting-lamp, substantially as set forth.

4. An electric night-lamp wherein are combined two incandescent electric lamps connected in series, a circuit-controller short-circuiting one lamp and another circuit-controller opening and closing the circuit to both lamps, substantially as set forth.

In testimony whereof I affix my signature in presence of two witnesses.

GODFREY HESS.
